1 Claim

ABSTRACT OF THE DISCLOSURE

An animal characterization pivotally connected at a lower forward point to a point on a wheel spaced radially outwardly from its center. The characterization forms a solid link between such point and an upper rear point of the characterization wherein it is pivotally connected to the lower end of a swinging link. A handle supports at its forward end an axle about which the wheel rotates, and extends rearwardly and upwardly from the axle. The link depends from a point on the handle rearwardly of the wheel.

The present invention relates to a trundling toy, and more particularly to a trundling toy comprising an animal characterization, and means for causing the characterization to move, as the toy is trundled, in a manner giving it the appearance of bounding, i.e., running in a succession of springs or leaps.

The trundling toy of the present invention is in the same general class with, but is distinguishable from, the trundling toys disclosed by the following U.S. patents: Dorn No. 224,585; Morrison No. 257,742; Ard No. 1,040,988; Savage No. 1,604,663; Gumb No. 2,361,196; Cohen No. 2,378,190; Schueger No. 2,432,817; Veress No. 2,522,076; and Cerino No. 2,541,404.

The animal characterization in the toy of the present invention is preferably a flat or two-dimensional, non-articulated cutout, from plywood, hardboard, sheet aluminum, sheet plastic etc. In addition to the animal characterization and the means for giving it the appearance of "bounding" as the toy is moved, the toy includes a support member. Preferably the support member is a push rod, which may be similar in construction to, and employed in the same manner as, the handle of a conventional carpet sweeper. According to the present invention, the means for giving movement to the animal characterization comprises a circular wheel rotatably mounted at its true center to the forwardly positioned lower end of the push rod; pivot pin means pivotally connecting the forward portion of the characterization to said wheel, at a point radially offset from the true center of the wheel; and a short swing arm pivotally attached at one of its ends to the push rod above the wheel, and pivotally attached at its other end to the rear portion of the characterization. As will be apparent, when the toy is trundled by a child, for example, holding the push rod at an acute angle with respect to the floor or other support surfaces, the forward portion of the animal characterization is moved in a vertically oriented circular path, in the directional rotation of the wheel, while the rear portion of the characterization swings back and forth along an arcuate path, like the bob of a pendulum, and about the point of pivotal connection of the swing arm to the push rod. The combined effect of these two movements is to give the characterization the appearance of bounding.

Another object of this invention is to provide a wheeled action toy of the above described character which is simple in construction, and which can be economically manufactured, and yet is durable in use and efficient in operation.

These, together with other objects and advantages, which will become subsequently apparent, reside in the details of

2

construction and operation of certain typical embodiments of the invention presently to be described, with reference being made to the accompanying drawing forming a part of this application, wherein like letters and numerals refer to like parts throughout, and in which:

5 FIG. 1 is a perspective view taken from above and toward the front and the animal characterization side of a trundling toy typifying the present invention;

10 FIG. 2 is a side elevational view of the toy shown by FIG. 1, looking toward the outboard side of the characterization, and showing the characterization in the position which it occupies when the pivot pin means connecting its forward position to the wheel is in its bottom-most position, and including a broken line showing of the circular path of travel of such pivot pin means, and a broken line showing of the two positions occupied by said pivot pin means when the swing arm is in its two end positions of movement, and showing by broken lines the two end positions of movement of the swing arm;

15 20 FIG. 3 is a view like FIG. 2, but showing the positions of the several parts after the wheel has rotated about an additional quarter of revolution, with the swing arm in such view shown to be very close to its rearwardmost position; and

25 25 FIG. 4 is a view similar to FIGS. 2 and 3, presenting a solid line showing of the relative positioning of the several parts upon about an additional quarter of a revolution of the wheel, and a broken line showing of the various parts in the position they occupy upon about 30 still another quarter of a revolution of the wheel.

35 Referring more specifically to the various figures of the drawing, the illustrated embodiment of the invention is shown to comprise a push rod 10 having a lower end portion 12 and an upper or "handle" end portion 14. By way of typical and therefore nonlimitative example, the push rod 10 may be a solid cylindrical rod of wood (i.e., a dowel) or plastic, or may be tubular metal, such as aluminum or aluminum alloy, or tubular plastic.

40 40 An axle, which may be in the form of a machine bolt 16, for example, extends laterally from the push rod 10 near the lower end 12. The axle 16 serves to rotatably mount a wheel W, which as illustrated may simply be a circular or disc cutout from a suitable sheet material, such as plywood or hardboard, for example. The wheel W is shown to be in juxtaposition with the lower end portion of the push rod 10, and the axle 16 is shown to extend through the true or geometric center of the wheel W. The axle 16 may be fixed relative to the push rod 10, with the wheel W rotating around it, or the axle 16 may be fixed relative to the wheel W, with it and the wheel W rotating together relative to the push rod 10.

45 45 The component of the toy that is the center of attraction is an animal characterization 18. Herein the term "animal" is used to mean fanciful (e.g., unicorns) as well as real animals. Preferably the animal is a quadruped depicted in the process of running. In other words, one of the front legs of the animal is positioned slightly ahead of the other, and the rear leg corresponding to the forwardly positioned front leg is itself positioned forwardly of the other rear leg. In the drawing a dog is shown by way of example, with its legs positioned in this manner.

50 55 Like the wheel W, the animal characterization 18 may be a flat or two-dimensional cutout, cut from plywood, hardboard, or a similar sheet material.

55 60 The animal characterization 18 is made to be substantially longer than the diameter of wheel W. The forward portion of the animal characterization 18 is in juxtaposition with the wheel W, on the side thereof opposite the push rod 10. Such forward portion is pivotally connected, preferably at a relatively low point, to a location on the wheel W that is radially offset from the true center C of the wheel W. The pivot pin 20 may simply be a screw with

a shank smaller than, and a head larger than, an opening drilled through, or otherwise formed in, the forward portion of the characterization 18. The threaded end of the screw 20 would be anchored in the wheel W.

As illustrated, the rear portion of the characterization 18 extends rearwardly of the wheel W. It is supported in a position above the support surface SS by a relatively short swing arm 22. The upper end of the swing arm 22 is pivotally connected at 24 to a point on the push rod 10 spaced along the push rod 10 above the wheel W. The lower end of swing arm 22 is pivotally connected at 26 to the rear portion of the characterization 18. Preferably, and as illustrated, the pivot point 26 is located at a relatively high point on the rear portion of the characterization 18.

The means establishing pivot point 24 may simply be a bolt passing through apertures in the push rod 10 and the swing arm 22, at least one of which apertures is enlarged, with the bolt being retained in place by a conventional nut. The means establishing pivot point 26 may be a screw extending through an enlarged hole in the animal characterization 18 and anchoring in the swing arm 22.

As illustrated, swing arm 22 may simply be a short, generally rectangular bar, with round ends, cut from a plank of wood or a piece of plywood, or formed of plastic or metal. In its assembled position, the swing arm 22 is disposed between the push rod 10 and the rear portion of the animal characterization 18, and is substantially coplanar with the wheel W. The diameter of wheel W, the amount of offset between center C and pivot point 26, the length of swing arm 22, and the various dimensions of the animal characterization 18, are all chosen so that during use of the toy the feet of the animal characterization 18 never touch the support surface SS.

In use, the push rod 10 is grasped at 14 and pushed on the support surface SS ahead of the user, similar to the manner in which a carpet sweeper is pushed. As the toy is moved forwardly, the wheel W rolls along the support surface SS, and the push rod 10 remains in a substantially constant position or attitude. Thus, the center of rotation C of the wheel W, which is a first pivot point, and the upper position of pivotal movement of swing arm 22 (i.e., point 24), which is a second pivot point, move in rectilinear translation. That is to say, a straight line interconnecting point C and 24 would remain substantially parallel to its initial position as the toy is moved. Since push rod 10 is rigid, the distance separating the point C, 22 remains constant, and these points C, 24 have no motion relating to each other.

The distance separating the third pivot point 20 and the fourth pivot point 26 is also always constant, because the animal characterization 18 is rigid, i.e., nonarticulated, between these two points.

As the toy is pushed forwardly pivot pin 20 is rotated about the true center C of the wheel W. As a result, the forward portion of the animal characterization 18 is moved along a substantially vertically oriented circular path of travel. As long as the toy is being moved forwardly, the movement of point 20 along the circular path is unidirectional. However, movement of connection point 26, and the rear portion of the animal characterization 18, is bidirectional, and along a flat, relatively short arcuate path.

As shown in FIG. 2, when the pivot point 20, the center C and the pivot point 26 lie in a straight line, with the pivot point 20 forwardly of the center C, the swing arm 22 is at its forwardmost position a. When these three points are aligned and the pivot point 20 is rearwardly of center C, the swing arm 22 is at its rearwardmost position of swing b. As will be apparent, as the pivot point 20 rotates from its position of alignment forwardly of point C back to its position of alignment rearwardly of point C, the swing arm 22, the pivot point 26, and the rear portion of the animal characterization 18 all swing from position a to position b. Then, as point 20 rotates forwardly from its aligned position rearwardly of point C to its aligned

position forwardly of point C, the swing arm, the pivot point 26, and the rear portion of the animal characterization 18 make the return swing from point b to point a.

To an observer the motion of the characterization 18 appears to be one of "bounding." In other words, as the toy is trundled forwardly, the animal characterization 18 appears to move with a succession of springs or leaps. During each cycle of the wheel W, the forward portion of the animal characterization 18 is displaced vertically an amount equal to twice the distance that the pivot point 20 is offset from the true center C of the wheel W. The rear portion of the characterization 18 is displaced vertically by a much smaller amount. This is near to what happens when a four legged animal moves in a succession of springs or leaps.

From the foregoing, various further modifications, arrangements and adaptations of the present invention will occur to those skilled in the art to which the invention is addressed. For example, the wheel W, the animal characterization 18, and the swing arm 22 may be duplicated on the opposite side of the push rod 10, so that a moving characterization is presented on both sides of the toy. Also the toy may be adapted to be pulled rather than pushed. This could be simply done by replacing the push rod 10 with a support member ending immediately rearwardly of pivot point 24, and having a forwardly extending handle portion.

What is claimed is:

1. In a wheeled action toy, rollable along a support surface:

a support member which maintains a substantially constant attitude during intended movement of the toy, said support member including means defining a first pivot point spaced above the support surface and a second pivot point which during the intended use of the toy is spaced both above the first pivot point and rearwardly therefrom in the direction of intended toy movement, said support member being rigid between said first and second pivot points so that they are always in a fixed position relative to each other;

an elongated animal characterization depicted to be in the process of running, said characterization having a front portion in the vicinity of said first pivot point and a rear portion in the vicinity of, but below, the second pivot point;

means defining a third pivot point in a lower front portion of the characterization and a fourth pivot point in an upper rear portion of the characterization, said characterization being rigid between said third and fourth pivot points, so that they are always in a fixed position relative to each other, and said characterization including a lower rear portion depicting rear legs which is always located below the fourth pivot point;

a circular trundling wheel rotatably attached at its true center to the support member at said first pivot point;

means pivotally connecting the front portion of the characterization, at the third pivot point, to the trundling wheel at a point thereof radially offset from such true center;

a relatively short swing arm depending below said second pivot point; and

means pivotally connecting the upper end of the swing arm to the support member, at the second pivot point, and means pivotally connecting the lower end of said swing arm to the rear portion of the animal characterization, at the fourth pivot point,

whereby as the wheel is rotated on the support surface the first and second pivot points move in rectilinear translation, the third pivot point moves in unidirectional rotation about the first pivot point, the fourth pivot point swings like a pendulum back and forth along an arcuate path situated entirely below and

3,455,050

5

centered at the second pivot point, and the animal characterization appears to be running in a succession of spring or leaps.
